METHOD AND APPARATUS FOR APPLYING
METALLIC SHEATHS TO CABLESLeigh E. Fogg, East Providence, R. I., assignor to
Kennecott Wire and Cable Company, Phillips-
dale, R. I., a corporation

Application May 11, 1939, Serial No. 273,155

8 Claims. (Cl. 207—4)

This invention relates to improvements in methods and apparatus for applying metallic sheaths to cables.

Heretofore in the art of applying metallic sheaths to electric cables, which sheaths ordinarily are of lead or lead alloy, considerable trouble has arisen from the presence of oxide and other foreign matter or impurities being present in the lead when it is extruded from the press into the form of a sheath about the cable and thus causing defects. One of the most serious reasons for the foreign matter causing trouble results from the fact that the sheathing press or lead press, as it is called, is of such limited capacity that it is unable to contain a sufficiently large charge of lead to extrude a sheath for a full length of cable. Therefore, as the sheathing press has to be recharged with molten lead one or more times in order to form a complete length of sheath on a single length of cable, there may be one or more welds or locations along the sheath where the successive lead charges join in the sheath, and it is particularly at these locations that the most serious defects due to impurities occur. Although many efforts have been made to eliminate the impurities from the lead in the press and thus avoid the difficulty of inferior and defective sheaths, this has not heretofore been satisfactorily accomplished.

I have found that by centrifugally treating the metal in molten condition before putting it in the sheathing press, that the impurities can be substantially entirely eliminated from the metal, so that a perfect sheath can be formed over a full length of cable, even at the locations where the successive charges of lead merge together.

One object of this invention, therefore, is to provide an improved method of substantially eliminating impurities from the metal in the sheathing press in order to make the sheath free from defects.

Another object of this invention is to provide improved apparatus for carrying out the foregoing method.

With the above and other objects in view, as will appear to those skilled in the art from the present disclosure, this invention includes all features in the said disclosure which are novel over the prior art.

In the accompanying drawings forming part of the present disclosure, in which one way of carrying out the invention is shown for illustrative purposes:

Fig. 1 is a schematic vertical sectional view il-

lustrating one embodiment of an apparatus for carrying out the invention;

Fig. 2 is a cross sectional view on line 2—2 of Fig. 1;

Fig. 3 is a cross sectional view on line 3—3 of Fig. 1; and

Fig. 4 is a cross sectional view on line 4—4 of Fig. 1.

In the description and claims, the various parts 10 and steps are identified by specific names for convenience, but they are intended to be as generic in their application as the prior art will permit.

Referring to the drawings showing the particular form of the invention chosen for illustration, the apparatus illustrated, in the main, comprises a melting furnace 10, a centrifugal separator 11, a supply or storage kettle or chamber or tank 12, and a sheathing press 13.

The melting furnace 10 may be constructed in 20 any suitable way, and is illustrated as having a melting chamber or pot 14 surrounded by a suitable heat insulation wall 15 which latter is enclosed by a casing 16. The pot 14 is heated by a suitable burner 17 which can receive gas or other 25 suitable heating medium through a pipe 18. Air-inlet openings 19 in the casing 16 provide an ample supply of air to the burner 17, and exit openings 20 provide an adequate exit for the burned gases from the burner. If desired, the melting furnace 10 may be provided with a suitable cover 10a, and a pipe 10b for introduction of steam or hydrogen or other suitable fluid medium into the melting chamber 14 or for providing a vacuum 30 therein, to maintain a non-oxidizing or reducing atmosphere in contact with the metal being melted in the melting chamber 14 or otherwise minimize or preclude oxidation.

The centrifugal separator 11 includes a lower fixed bearing 21 on which is rotatably mounted 40 a centrifugal bowl or cylinder 22, which bowl 22 has a shaft 23 rotatably mounted in a fixed upper bearing 24 forming part of a spider 25 having its rim portions 26 and 27 respectively fitting within, and resting upon the upper edge of, the 45 upper rim portion 28 of a storage or circulating tank 29.

The shaft 23 may be rotated by means of any suitable means such as an electric motor 30 acting through a belt or chain 31 which drives a shaft 32, which rotates the shaft 23 of the bowl 22 by any suitable connection such, for example, as a friction coupling 33.

A cover 34 is hinged at 35 to a bracket 36 50 secured to the rim portion 28 of the tank 29, and

has the parts 30, 31, 32 and part of coupling 33 carried thereon, so that when the cover 34 is swung down to the position shown and locked by the bolt 37 and nut 38, the parts of the coupling 33 are in driving engagement with one another, so that the motor 30 can rotate the centrifugal bowl 22. A flexible or other suitable pipe or tube 39 leads through the cover or other suitable part of the tank 29 to provide for the introduction of steam or hydrogen or other suitable fluid medium or to provide a vacuum in the tank, to maintain a non-oxidizing or reducing atmosphere in contact with the metal being purified by the centrifugal separator or otherwise preclude or minimize oxidation. The tank 29, at its lower end carries the lower bearing 21 of the centrifugal separator 11.

The sheathing press or lead press 13 can be of any suitable or usual form, and in the form shown includes a cylinder 40 and a power-actuated piston or ram 41 adapted to slidably fit the inner cylindrical surface of the cylinder 40. The cable 42 to be sheathed, is adapted to extend completely through the lower part of the sheathing press 13 including the sheathing die 43 at the far side of the press, in a manner that is usual and well-known in the art.

A pipe 44 leads from the bottom of the melting pot 14 through a control valve 45 to a T 46, and thence in one direction downwardly through a drain valve 47 and a drain pipe 48, and in the opposite direction upwardly through a pipe section 49 to the interior passage 50 of the bearing 21 and into the centrifugal cylinder or bowl 22. One or more inlet or ingress ports or openings 51 provide ingress into the passage 50 leading to the centrifugal bowl 22, from the interior 52 of the storage or circulation tank or kettle 29. The ingress openings 51 can be controlled by any suitable valve means such, for example, as the rotary valve-sleeve 53 having an arm 54 provided with a slot 55 engaged by the end of a rod 56 slidably extending through a lead-tight packing-connection 57 and carrying an operating knob 58. One or more egress or outlet openings or ports 59 are provided at the upper end of the centrifugal bowl 22. The egress port or ports will have a suitably smaller cross-sectional area than the ingress port or ports to ensure that the centrifugal cylinder remains fully charged with both lead and the separated impurities.

A pipe 60 leads from the interior 52 of the tank 29 through a control valve 61 and through the passage 62 into the interior chamber 63 of the cylinder 40 of the sheathing press 13.

Although heat insulation has only been shown as surrounding the melting pot, it will be appreciated that any other parts of the apparatus that it is found preferable to have surrounded with heat insulation material can be readily so provided to aid in retaining the metal in molten condition at all locations from the melting pot to the sheathing press. Also, electrical or other suitable heating means may be provided where desired to aid in maintaining the metal in molten condition.

Instead of having the storage tank 29 surrounding the centrifugal separator 11, a storage tank or kettle could be arranged away from the centrifugal separator with suitable piping leading from the outlet openings 59 of the separator in accordance with principles and constructions well understood in the centrifugal separator art. Also, instead of having the pipe 60 connected to the storage tank, it could be directly connected

with a channel leading from the outlet openings 59 of the centrifugal separator, thus entirely eliminating the use of any storage or re-circulating tank. Or, a supply or storage tank or kettle for molten metal could be in the form of a separate sealed kettle.

When a charge of metal has been melted in the melting pot 14 and brought to a desired temperature, the drain valve 47 is closed, valve-sleeve 53 is rotated by the knob 58 to close the ports 51, and control valve 45 is opened to permit the molten metal to flow from pot 14 through the pipes 44 and 49 into the interior 50 of bearing 21 and into the centrifugal bowl or cylinder 22, which when adequately full, is set into operation by starting the motor 25. The centrifugal force created by the rotating metal in the rotating centrifugal cylinder 22 causes the impurities, which are lighter than the molten metal, to be forced by the heavier metal to move inward toward the center of the rotating mass of molten metal. As the mass of molten metal speeds up, it rises in the centrifugal cylinder and starts passing out of the egress ports 59. The molten metal which passes out through the egress ports 59 drops down into the interior of the tank 29 until the molten metal in the tank 29 rises to such a height as is desired, whereupon the control valve 45 is closed and the knob 58 is actuated to rotate the valve-sleeve 53 to open the ingress ports 51, whereupon molten metal flows by gravity through the ingress ports 51 and upwardly through the center opening 50 to constantly replenish the supply of metal that is being centrifugally purified within the cylinder 22 and thrown out through the egress ports 59. The egress ports 59 are of suitably less total area than the total area of the ingress ports 51 so that a sufficient amount of molten metal can enter the centrifugal cylinder to maintain the latter adequately full.

Thus, as the centrifugal cylinder 22 continues to rotate, the metal in the vicinity of the cylinder wall moves up and flows out of the egress ports 59, and other metal flows in the ingress ports 51, thus bringing about a circulation of the body of molten metal in the tank 29 to thus subject this mass of metal to repeated purification. If desired, at any time, the centrifugal separator can have its rotation stopped, the valve-sleeve 53 can be closed, and the drain valve 47 can be opened to drain out the lead within the cylinder 22 with the impurities contained therein.

Upon the control valve 61 being opened by turning the handle 67, purified lead can flow from the tank 29 through the pipe 60 into the interior 63 of the sheathing press 13, the filling of the chamber 63 being facilitated by raising the ram 41 which tends to cause a vacuum. If undercut groove means 66 is avoided in the underface of the ram 41, it will aid in causing the residual lead adjacent the ram to be drawn up with the ram, thus leaving the inner end of the passage 62 unobstructed. The control valve 61 is then closed by properly turning its handle 67.

When the ram 41 is caused to move down under power to press the plastic metal in the chamber 63, plastic lead is formed into a solid metal sheath 64 surrounding the cable 42, as the cable moves from left to right as indicated by the arrow 65 in Fig. 1.

When the ram reaches the end of its downward movement, it is caused by the operator to be actuated to be retracted upward again to draw in a renewed supply of molten metal. The

ram is then again caused to move downward to force molten metal to continue to form another section of sheath about the cable 42. The operation is repeated as often as necessary to completely sheath a complete length of cable.

Thus, it will be seen that by interposing a centrifugal separator between a melting chamber and a sheathing press, whether or not any storage tank is employed in connection with the centrifugal separator, all metal fed to the sheathing press will have been centrifugally purified so as to be substantially free of oxides or other impurities, and thus permit of applying metal sheaths to cables with the metal sheaths substantially perfect and free from oxides or other impurities, throughout all portions of the sheath.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. The method of applying lead-base metallic sheaths to electric cables, comprising: centrifugally removing impurities from lead-base sheath metal while in a molten condition and forming said centrifugally purified lead-base sheath metal into a sheath on an electric cable.

2. Apparatus for applying lead-base metallic sheaths to electric cables, including: a sheathing press for forming lead-base sheath metal into a sheath on a cable; a centrifugal separator constructed and arranged to retain a substantial body of molten lead-base sheath metal and centrifugally remove impurities from the said molten metal by causing the impurities to travel to the interior portion of the body of molten metal; a tank for receiving said centrifugally purified lead-base sheath metal from said centrifugal separator; and means for conveying said centrifugally purified lead-base sheath metal from said tank into said sheathing press.

3. Apparatus for applying metallic sheaths to cables, including: a sheathing press for forming sheath metal into a sheath on a cable; a centrifugal separator for centrifugally removing impurities from sheath metal while in a molten condition; a tank adapted to recirculate molten sheath metal through said centrifugal separator; and means for conveying said centrifugally purified sheath metal into said sheathing press.

4. Apparatus for applying metallic sheaths to cables, including: a sheathing press for forming sheath metal into a sheath on a cable; a centrif-

ugal separator for centrifugally removing impurities from sheath metal while in a molten condition; a tank surrounding said centrifugal separator and adapted to recirculate molten sheath metal through said centrifugal separator; and means for conveying said centrifugally purified sheath metal into said sheathing press.

5. Apparatus for applying metallic sheaths to cables, including: a sheathing press for forming sheath metal into a sheath on a cable; a centrifugal separator for centrifugally removing impurities from sheath metal while in a molten condition; drain means communicating with the lower end of said centrifugal separator; and means for conveying said centrifugally purified sheath metal into said sheathing press.

6. Apparatus for applying metallic sheaths to cables, including: a melting chamber for sheath metal; a sheathing press for forming sheath metal into a sheath on a cable; and a centrifugal separator for centrifugally removing impurities from sheath metal while in a molten condition having an inlet end communicating with said melting chamber for receiving molten sheath metal therefrom and an outlet end communicating with said sheathing press for conveying said centrifugally purified sheath metal into said sheathing press.

7. Apparatus for applying lead-base metallic sheaths to electric cables, including: a centrifugal separator constructed and arranged to retain a substantial body of molten lead-base sheath metal and centrifugally remove impurities from the said molten metal by causing the impurities to travel to the interior portion of the body of molten metal, and to cause purified molten metal to be removed from the said centrifugal separator from the exterior portion of the body of molten metal without carrying with it any of the impurities which had been caused to travel to the interior portion of the body of molten metal.

8. Apparatus for applying lead-base metallic sheaths to electric cables, including: a centrifugal separator constructed and arranged to retain a substantial body of molten lead-base sheath metal and centrifugally remove impurities from the said molten metal by causing the impurities to travel to the interior portion of the body of molten metal, and to cause purified molten metal to be removed from the said centrifugal separator from the exterior portion of the body of molten metal without carrying with it any of the impurities which had been caused to travel to the interior portion of the body of molten metal, said centrifugal separator having an inner inlet and an outer outlet for the molten metal.
